UNITED STATES PATENT OFFICE.

HUGH MCBAIN, OF ST. LOUIS, MISSOURI.

CONNECTING-ROD AND PISTON ALIGNING TOOL.

Application filed May 7, 1923. Serial No. 637,280.

This invention relates to connecting-rod-and-piston-aligning tools and has for its object to provide a simple, compact, and readily adjustable tool for testing the parallelism of connecting-rod bearings and their perpendicularity to the piston.

In the accompanying drawings forming part of this specification, in which like numbers of reference denote like parts wherever they occur,

Figure 1 is a plan view of the complete device;

Figure 2 is an enlarged vertical sectional view, taken through the supporting rod, of a modified form of bracket for supporting an alternate form of indicator;

Figure 3 is a transverse sectional view taken on the line 3—3 of Figure 2;

Figure 4 is a front elevation of the complete device;

Figure 5 is an enlarged view of the type of indicator and bracket shown in Figures 1, 4, and 7, a transverse section of the bracket and a portion of the indicator being taken on the lines 5—5 of Figure 4;

Figure 6 is an enlarged rear view of the indicator and bracket illustrated in Figures 1, 4, and 7; and

Figure 7 is an end view of the complete device.

Referring to the drawings, a rectangular block 1 has opposing sides 2 and 3 provided with centrally disposed bosses 4 and 5 respectively. Lugs 6 project perpendicularly from the side 2 at its lower corners, and lugs 7 extend diagonally outward from the side 3 at its lower corners. The lugs 6 and 7 are provided with vertical holes 8 for the reception of screws by means of which they may be secured to a table or bench. A hole may be bored centrally through block 1 and bosses 4 and 5 for the reception of a mandrel 9, or, preferably, mandrel 9 may be cast integral with bosses 4 and 5 and turned true in a lathe. The top surface 10 of block 1 is provided with a rectangular groove or slot 11, parallel to mandrel 9 and having its center line in the vertical plane which passes through the mandrel axis. Similar grooves 12 and 13 are arranged in the top 10 parallel to and at equal distances from the groove 11. Grooves 11, 12, and 13 have accurately and truly planed sides 14 and bottom 15.

A rectangular block 16 fits slidably in the grooves 11, 12, and 13 and is provided with a longitudinal slot 17 in its bottom for the purpose of reducing friction during sliding movement thereof and further having a flat upper face 19. A vertical cylindrical rod 20 has a lower end 21 of reduced diameter which fits snugly in a central hole 22 extending through the block 16, and, also, has a shoulder 23, which abuts against the top 19. The top end 24 is beveled at 25, and a slot 26 is milled in the rear of the rod 20.

Rod 20 passes through a hole 27 near one end of longitudinal bracket 28, which can be secured at any convenient height by tightening set-screw 29, fitting in tapped hole 30 in bracket 28 and having its point 31 seating in slot 26. The other end of bracket 28 has a vertical slot 32, within which fits a shoe 33 pivoted at its center 75 on a screw 34 passing through bracket arm 35 and fitting into tapped hole 36 in bracket arm 37. Shoe 33 has a vertical front face 38, whose vertical continuity is interrupted in the middle by a recess 39, and, also, has a rear face 40 for contact with a projection 41 of a micrometer indicator 42 of the watch-case type. Indicator 42 is supported by a vertical bracket 43, secured to the rear of bracket 28 by screws 44 and having a horizontal slot 45, in which fits tongue 46 of clamping plate 47. Bracket 43 is clamped between boss 48 of indicator 42 and between shoulders 49 of plate 47 on tightening screws 50, which pass through plate 47 and fit into tapped holes 51 in indicator 42. Semi-circular recesses 52 in bracket 43, and a transverse cylindrical hole 53 through the middle of bracket 28 are provided for purposes of ornamentation and for reducing the weight of the respective parts, as well as for affording convenient means for grasping the same.

In the use of this tool, the indicator 42 is preferably so adjusted that the pointer 54 100 is on the zero mark of the dial when surface 38 is truly perpendicular to the axis of the mandrel 9. To facilitate the making of this adjustment, a truly horizontal flat spot 55 is provided along the top of the mandrel 9 for convenience in contacting with the horizontal edge 56 of a square 57, the vertical edge 58 of which is preferably held

against trued face 59 of boss 5. Block 16, with its associated parts, including indicator 42 and shoe 33, is now placed in slot 11 and advanced toward vertical edge 58 of square 57 until surface 38 is in intimate contact throughout its entire length with edge 58. Screws 50 are now loosened and indicator 42 moved toward or away from face 40 until the pointer 53 is on the zero mark, after which screws 50 are again tightened. A connecting-rod 60 to be tested is now first secured in a vertical position with its piston 61 on top, by clamping its crank-shaft bearing 62 around the mandrel 9, in the event that a minimum size connecting-rod is under test. However, if it be desired to test a connecting-rod having a crank-shaft bearing of larger diameter, it is necessary to interpose a suitable bushing 63 between the mandrel 9 and the crank-shaft bearing 62, a plurality of such bushings of different thickness being provided to accommodate the tool to various sizes of connecting-rod bearings. Bushing 63 is split along its entire length at 64 to reduce its rigidity and render yieldable to the clamping action of the bearing, so that the same may be transmitted to the mandrel 9, and is preferably placed with its slit 64 in registration with the meeting surfaces of the two bearing halves. Block 16, with its associated parts, including indicator 42 and shoe 33, is now placed in slot 11 and advanced toward piston 61 until surface 38 is in intimate contact with piston 61 along its entire length. If the pointer 54 now indicates zero the piston 61 is perpendicular to the bearing 62 in this position, that is, when the axis of the piston 61 and the axis of the bearing 62 lie in the same plane. The reading just taken, however, can not reveal any twist in the connecting-rod, if such there be, because both wrist-pin bearing 65 and crank-shaft bearing 62 lie in parallel horizontal planes in this position. If, however, connecting-rod 60 is inclined, and the piston appears vertical when viewed as in Figure 7, and when the block 16 with associated parts and indicator 42 is placed in groove 12, as indicated in dotted line, then any twist in the connecting-rod with the attendant angularity between wrist-pin and crank-shaft bearings at once becomes apparent, since if this condition prevails the element of piston 61 in contact with surface 38 will be inclined from the vertical, and the indicator will not read zero. A similar test is, also, made in the opposite direction in groove 13.

It is not to be understood, however, that this device is limited in its use to the particular form of indicator 42 of the watch-case type. Any suitable type of indicator may be used. In Figures 2 and 3, an alternate type of indicator is depicted. In this construction the alternate form of bracket

66 has a slot 67, which extends nearly to the post 20, and divides the bracket 66 into arms 68 and 69. Arm 68 supports a lever indicator 70, such as may be bought in the open market, in the slot 67, by means of screws 71 and 72, which fit in tapped holes 73 in indicator frame 74. Screw 71 passes through a hole 75 in arm 68 and screws 72 through a slot 76 in arm 68. Pointer 77 is pivoted at 78 to frame 74 and knob 79 of pointer 77 is held in engagement with face 40 by the action of a spring 80, whose tension can be regulated by rotating notched disk 81 secured by screw 82. In adjusting this indicator, screws 71 and 72 are loosened, and the frame 74 swings on screw 71 as a center, and the screws 71 and 72 again tightened when the proper position has been determined.

Having thus described this invention, I hereby reserve the benefit of all changes in form, arrangement, order, or use of parts, as it is evident that many minor changes may be made therein without departing from the spirit of this invention or the scope of the following claims.

I claim:

1. In a tool of the character described, the combination of a supporting block having a plurality of parallel guide grooves, a mandrel borne by the said block, a test tool, and carrying means for the said test tool adapted to be placed in any one of said guide grooves and be moved parallel to said mandrel.

2. In a tool of the character described, the combination of a supporting member, a mandrel borne by the said member, a block slideable on said member, a testing tool, a holder for the testing tool, and means borne by the said block and on which the said holder is slideable perpendicularly to the direction in which said block is adapted to slide on the said supporting member.

3. In a tool of the character described, the combination with a supporting member having a plurality of parallel guide grooves in one face thereof, a crank-supporting mandrel carried by said member and extending longitudinally of said grooves, test-tool carrying means adapted to be placed in any one of said guide grooves for enabling a plurality of tests to be made with the crank inclined in different directions, and adapted to be moved longitudinally of the said guide grooves to be adjusted longitudinally of the said mandrel, and a test tool carried by the said means.

4. In a tool of the character described, the combination of a supporting member having a plurality of parallelly disposed guide grooves arranged on its top surface, connecting-rod supporting means carried by said member and having its axis disposed parallel to said grooves, a test tool, and test-tool-supporting means carried by said mem-

ber and cooperating with its grooves for effecting the horizontal adjustment of said test tool.

5. In a tool of the character described, the combination of a supporting member having a plurality of parallelly disposed guide grooves arranged on its top surface, connecting-rod-supporting means carried by said member and having its axis disposed parallel to said grooves, a block slidably mounted in

any one of said grooves, a bracket adjustably connected to said block, and a test tool carried by said bracket and subject to vertical and horizontal adjustment through the intermediary of said slideable block and bracket.

In testimony whereof I hereunto affix my signature.

HUGH McBAIN.
